CORNPICKER ROLL

Edgar V. Collins, Ames, Iowa

Application November 13, 1950, Serial No. 195,403

9 Claims. (Cl. 56—111)

1

This invention relates generally to corn harvesting machines and in particular to rolls in a cornpicking machine adapted to continuously gather the stalks, and to husk and pick ears from the stalks, as the stalks travel axially in succession between the rolls.

An object of this invention is to provide an improved corn harvesting machine.

Another object of this invention is to provide a pair of cornpicker rolls having sections of different diameters and with the sections being operated at different speeds and relatively arranged in the rolls so that standing stalks passing between the rolls are continuously husked and picked with the husks remaining on the standing stalks.

A further object of this invention is to provide cornpicker rolls of a relatively small diameter and rotated at relatively high speeds which are capable of picking corn ears from their associated husks and stalks without any substantial grabbing, shelling or mutilation of the butt ends of the ears.

Still another object of this invention is to provide cornpicker rolls capable of efficiently picking small ears or nubbins.

Yet a further object of this invention is to provide cornpicker rolls capable of advancing standing stalks therebetween in succession, and during such advance to pick ears from the stalks, free of any husks, so as to leave the stalks with the husks thereon remaining in the field.

A further object of this invention is to provide a two-section cornpicker roll, in which the sections are of different diameters independently supported for rotation at their adjacent ends, such that one side portion of the roll is in linear continuity over the full length of the roll.

Further objects, features and advantages of this invention will become apparent from the following description when taken in connection with the accompanying drawings in which:

Fig. 1 is a top plan view of the cornpicker rolls of this invention illustrated in assembly relation with a fragmentary showing of a cornpicker machine;

Fig. 2 is an enlarged sectional detail view of a cornpicker roll of this invention taken substantially along the line 2—2 in Fig. 6;

Fig. 3 is a sectional view taken along the line 3—3 in Fig. 2;

Fig. 4 is a sectional detail view as seen on the line 4—4 in Fig. 2;

Fig. 5 is a side elevational view of the roll assembly shown in Fig. 1; and

Fig. 6 is a sectional view taken substantially along the line 6—6 in Fig. 5.

Referring to the drawings, the rolls 10 of this invention are illustrated in Fig. 1 in assembly relation with a cornpicker machine, designated generally at 11, and including a frame structure 12 which movably carries usual stalk gathering chains 13 in operative association with

2

gathering snouts 14. An elevator for conveying picked corn to a wagon is indicated at 16. The rolls 10 are arranged longitudinally of the machine 11 in upwardly and rearwardly inclined positions, as best appears in Fig. 5. Since the rolls 10 are of a like construction only one thereof will be referred to in detail in the following description.

A roll 10 (Fig. 1) is comprised of two sections 17 and 18, with the front or gathering section 17 being of a greater diameter than the rear or picking and husking section 18. The roll 10 is rotatably supported in the machine 11 by the provision of a front bearing 19 secured to a member 21 of the frame structure 12 and assembled in a well-known manner with the front section 17 at a position spaced rearwardly from its front end 22. A bearing member 23 on a frame member 24 of the frame structure 12 supports the roll 10 at the rear end 26 of a rear section 18.

The front section 17 of a roll 10 (Figs. 2 and 3) is of a hollow cylindrical construction open at its rear end 27 and with its front end 22 being closed and of a tapered construction. The sections 17 and 18 of a roll 10 are rotatably supported at their junction by a combination bearing and gear reduction unit, designated generally as 28, and which includes a bearing block 29 received within the rear end 27 of the front section 17 so as to be within the longitudinal or axial confines of the section 17. The bearing block is formed at its front end 31 with a bearing support 32, coaxial with the front section 17. Mounted on the bearing support 32 is a roller bearing assembly 33 about which the rear end 27 of the front section 17 is rotatably supported.

Transversely offset from the bearing support 32, and formed in the rear end 34 of the bearing block 29 is a cylindrical cavity 36, open to one side of the bearing block 29, for receiving a self-aligning bearing assembly 37, which is in coaxial alignment with the roll rear section 18. The rear section 18 has its front end 38 of a reduced diameter so as to constitute a shaft portion for insertion within the self-aligning bearing 37 to a position such that the shoulder 39 formed at the rear end of the shaft portion 38 is closely adjacent to the rear end faces 41 and 42 of the front section 17 and bearing block 29, respectively.

It is seen, therefore, that the front section 17 is rotatably supported at the bearings 19 and 33 for rotation independently of the rear section 18 which is rotatably supported at the bearings 23 and 37. The bearing block 29 is retained stationary by a bracket member 43 secured to the frame member 21 and to the rear end 34 of the bearing block by bolts 44. As best appears in Fig. 1, the bracket 43 is projected laterally from a front section 17 in a direction away from the support of the rear section 18 on the bearing block 29.

The rear end 27 of a front section 17 terminates in an internal gear 46 which is in meshed engagement with a pinion gear 47 mounted on the shaft portion 38 so as to be within the front section 17. The bracket 43, as shown in Fig. 6, is cut away at 48 so as to be in a clearance relation with the rear section 18. It is seen, therefore, that the gear assembly, comprising the internal gear 46 and the pinion gear 47, is enclosed within the front section 17 by the bracket 43 and shoulder 39 of the rear section 18.

With reference to Fig. 2 it is seen that the self-aligning bearing 37 is offset transversely from the bearing support 32 such that the side portions 49 and 51, of the sections 18 and 17, respectively, are located opposite the side 50 of the section 17, from which the mounting bracket 43 projects, are in substantial linear alignment axially of the roll 10. Further, by virtue of the location of the combination unit 28 within the front section 17 and the close adjacency of the rear end face 41 of the front section 17 to the shoulder 39, it is seen that the side portions 49 and 51 are substantially continuous over the full length of the roll 10.

In use, the rolls 10 are arranged longitudinally of the picker machine 11 in a transversely-spaced relation (Fig. 1) such that the continuous side portion of a roll, comprised of the portions 49 and 51 of the sections 18 and 17, respectively, are opposite each other so as to constitute the side or defining walls of the space 52 between the rolls 10. As a result, the space 52 is of a substantially constant width over the full length of the rolls 10. The rear ends 26 of the sections 18 carry meshed gears 53, and with a rear shaft extension 54 on one of the rolls 10 being suitably connected with a source of power (not shown), such as the power take off of a tractor. The shaft extension 54 is rotated in a direction such that the rolls 10 are reversely rotated inwardly toward each other as indicated by the arrows in Fig. 6.

In operation, and referring to Fig. 1, as the machine is advanced along a corn row the corn stalks, indicated at 56, enter the rolls between the tapered sections 22 and are then advanced rearwardly of the front sections 17 by reversed spiral flights 57 formed on the sections 17. The peripheral surface of each rear section 18 (Figs. 2 and 4) is formed with what might be termed hobs 58 arranged in circumferential rows spaced axially of a rear section and with the rows being in parallel planes inclined relative to the axis of a rear section. Each hob 58 is of a substantially pyramid shape, so that as a stalk passes within the space 52 between the rear sections 18 it is pierced rather than crushed by the action of the hobs. It is contemplated that the hobs stand about one-eighth of an inch high and that the hobs be about a quarter of an inch apart at the space 52.

In one embodiment of the invention the rear sections 18 are about one and three quarters inches in diameter and rotated at a speed of about 1030 R. P. M. In this embodiment the front sections 17 are about three inches in diameter and rotated at a speed of about 350 R. P. M. As the stalks 56 pass between the rear sections 18 any grabbing action on the butt ends of the ears of corn is substantially eliminated by the hob formation of the peripheral surfaces of the sections 18. Further, due to the relatively small diameter of the rear sections 18 and their rotation at a relatively high rate of speed, the ears are repelled or rejected from entering the sections 18 instead of being drawn therebetween.

As a result of this action of the roll sections 18 the machine is capable of efficiently picking small ears of corn, without crushing them, and of picking large ears of corn without mutilating or destroying the butt ends of such large ears.

In this picking action, the ears are picked from the stalks free of any husks. Stated otherwise, the husks are removed from the ears, and the ears from the stalks, so that the rear sections 18 function as combination picking and husking rolls. The picked ears are then directed to the wagon elevator 16, while the husks pass downwardly between the rear sections 18 secured on the standing stalks.

In the travel of the stalks between the rear sections 18 it has been found that the upper ends of the stalks tend to accumulate or become bunched together at the front or lower ends of the rear sections 18. By virtue of this collecting tendency the picking action of the sections 18 is confined somewhat to their lower ends. Since the picked ears would also fall along the lower ends of the roll sections 18, they relatively interfere with their free passage into the wagon elevator 16.

To overcome this accumulation of the stalks and ears at the lower ends of the sections 18 there is provided a feeding auger 61 (Figs. 1, 5 and 6) located in a parallel-spaced relation with and above the rolls 10 at a position between the rolls and the wagon elevator 16. In the embodiment of the invention above referred to the auger 61 has a diameter of about ten inches. The auger 61 is rotatably supported in the frame members 24 and 62 of the frame structure 12 and has a shaft extension 63 at its rear end for carrying a sprocket gear 64. The gear 64 is connected through a sprocket chain 66 with a sprocket gear 67 mounted on the shaft extension 54 on one of the rolls 10. As the stalks 56 (Fig. 5) pass between the rear sections 18 their upper ends 57 are engaged by the spiral flights 68 of the auger 61 and advanced in a spaced relation upwardly or rearwardly of the roll sections 18.

For directing the picked ears toward the wagon conveyer 16, and the upper stalk ends 57 into the auger 61 it is contemplated that the rolls 10 be arranged in a plane which is inclined upwardly toward the auger shaft 69 as best appears in Fig. 6. In the embodiment of the invention referred to above this angle of inclination is about fifteen degrees relative to a vertical plane passing between the rolls 10. The angle of inclination is adjustable by the provision of arcuate slots 71 formed in the brackets 43 for receiving the bolts 44.

From the above description it is seen that the invention provides a pair of corn picker rolls each of which is comprised of a front gathering section and a rear husking and picking section, and with the sections in a roll being of different diameters and operated at different speeds of rotation. The rolls are capable of gathering stalks in a corn row, and on travel of the corn-picking machine advance the stalks in succession therebetween to continuously pick and husk the ears, leaving the husks remaining on the standing stalks. By virtue of the construction of the roll sections 18, and their rotation at relatively high speeds, both small and large ears are efficiently picked with a minimum shelling of corn.

Although the invention has been described with respect to a preferred embodiment thereof it is to be understood that it is not to be so

limited since changes can be made therein which are within the full intended scope of this invention as defined by the appended claims.

I claim:

1. In a corn harvesting machine, a two-section roll having a front stalk gathering section, and a rear picking and husking section, with said rear section being of a reduced diameter relative to said front section, bearing means at the junction of said two sections for rotatably supporting the rear end of said front section, other bearing means at said junction for rotatably supporting the front end of said rear section at a position such that one of the corresponding side portions of said sections is in substantial linear alignment axially of said roll, and means at said junction connecting said sections for concurrent rotation at different rotational speeds.

2. In a corn harvesting machine, a two-section roll having a front stalk gathering section and a rear picking and husking section, with said rear section being of a reduced diameter relative to said front section, and means rotatably supporting said sections at the adjacent ends thereof for independent rotation, with said adjacent ends being offset transversely of the roll at said supporting means such that one side portion of said roll is substantially continuous over the full length of the roll.

3. In a corn harvesting machine, a two-section roll having a first section of a reduced diameter relative to a second section, means for rotatably supporting the adjacent ends of said two sections including a bearing member positioned within the adjacent end of said second section and having a pair of bearing portions, with the adjacent end of said second section being mounted about one of said bearing portions, and the adjacent end of the first section being received within the other of said bearing portions, with said bearing portions being offset transversely of said bearing member such that a side portion of said roll is in linear alignment over the full length of the roll.

4. In a corn harvesting machine, a two-section roll having a first section of a reduced diameter relative to the second section thereof, with the adjacent end of said second section at the junction of said two sections being hollow, a combination bearing and gear reduction unit positioned within the hollow end of said second section having a mounting member located outwardly from said hollow adjacent end and projected laterally to one side of said roll, a first bearing portion on said bearing unit for rotatably supporting the hollow adjacent end of said second section, a second bearing portion on said unit, with the adjacent end of said first section being inserted within said second bearing portion so that the adjacent ends of said two sections are in a longitudinally overlapped relation, a pinion gear on the adjacent end of said first section located within the hollow adjacent end of said second section, an internal gear on said hollow adjacent end in meshed engagement with said pinion gear, with said bearing portions being relatively arranged such that the side of said roll, substantially opposite from said one side thereof, is in linear continuity over the full length of the roll.

5. A two-section roll for a corn harvesting machine including a front stalk gathering section and a rear picking and husking section, with said rear section being of a reduced diameter relative to said front section, and a combination bearing

and speed reduction unit at the junction of said two sections located within the dimensional confines of said front section for independently rotatably supporting the adjacent ends of said two sections for rotation at varying speeds, with said adjacent ends being transversely spaced within said combination unit such that peripheral portions of said two sections at one side of the roll are in linear alignment axially of the roll.

10 6. A corn harvesting machine having a pair of transversely spaced upwardly and rearwardly inclined sectional rolls, with each of said rolls having a front stalk gathering section and a rear husking and picking section, and with said rear sections being of a reduced diameter relative to said front sections, means rotatably supporting said sections for relative rotation such that side portions of a corresponding front and rear section at said space are in linear alignment axially of a corresponding roll, means for rotating said rear sections at a greater rotational speed than said front sections, and a stalk feeding mechanism mounted above said rear sections including a spiral member engageable with the 15 upper ends of stalks passing between said rear sections to rearwardly advance said stalk upper ends.

7. In a corn harvesting machine, a two section roll having a front stalk-gathering section and a 20 rear picking and husking section, with said front section being of an enlarged diameter relative to said rear section, bearing means at the adjacent ends of said front and rear sections for supporting said sections for relative rotation, and means 25 on said roll providing for a concurrent rotation of said sections at different rotational speeds.

8. In a corn harvesting machine, a section- 30 alized roll having a front stalk-gathering section and a rear picking and husking section, with said front section being of an enlarged diameter relative to said rear section, means on said roll for supporting said front and rear sections for relative rotation, and means on said roll providing for a concurrent rotation of said sections at different rotational speeds.

45 9. In a corn harvesting machine, a pair of transversely spaced substantially parallel rolls, with each roll having a front section and a rear section, with a rear section being of a reduced diameter relative to a corresponding front section, and means supporting corresponding front and rear sections in a roll for relative rotation, with a rear section having the axis thereof transversely offset relative to the axis of a corresponding front section such that a side portion of a roll is in linear alignment over the full length of the roll whereby when said side portions of said rolls are disposed opposite each other the space between said rolls is of a substantially constant width over the complete length of the rolls.
